(57) CLAIM

I claim the ornamental design for a dog collar slip cover, as shown and described herein.

DESCRIPTION

FIG. 1 is a back view of a dog collar slip cover according to my new design;

FIG. 2 is a front view thereof;

FIG. 3 is a back view thereof, shown with a dog collar being inserted into the slip cover for illustrative purposes;

FIG. 4 is a back view thereof, shown with a dog collar being slid further into the slip cover, for illustrative purposes;

FIG. 5 is a back view thereof, shown with a dog collar completely inserted into the slip cover, for illustrative purposes; and,

FIG. 6 is a reduced scale perspective view of a dog collar slip cover, shown worn on a dog for illustrative purposes. The broken line showing of a dog collar in FIGS. 3–4, as well as that of a dog, in FIG. 6, are for illustrative purposes only and form no part of the claimed design. All other dashed lines in the drawings represent stitching, and are part of the claimed design.
